(57) **CLAIM**

The ornamental design for a headband, as shown and described.

DESCRIPTION

FIG. 1 is a top, front, right side perspective view of a headband showing my new design;

FIG. 2 is an enlarged front elevation view thereof;

FIG. 3 is an enlarged rear elevation view thereof;

FIG. 4 is an enlarged left side elevation view thereof;

FIG. 5 is an enlarged right side elevation view thereof;

FIG. 6 is a top plan view thereof;

FIG. 7 is a bottom plan view thereof; and,

FIG. 8 is a top, front, right side perspective thereof with a pair of headphones mounted thereon in condition of use.

The broken lines in the drawings illustrate portions of the headband that form no part of the claimed design.

The headphones outlined by broken lines in the view of FIG. 8 assists to illustrate the headband in condition of use that form no part of the claimed design.

1 Claim, 8 Drawing Sheets
